UNITED STATES PATENT OFFICE

JOSEPH P. MCENERY, OF FLUSHING, NEW YORK

PENCIL HOLDER

Application filed April 19, 1932. Serial No. 606,089.

This invention relates to pencil holders and the like and has for an object an inexpensive efficient and serviceable combined pencil holder and clip for attaching the same to an object such, for example, as a folded score card, dance program or the like in such manner that the card is held closed with the pencil covered by the card.

A holder embodying the invention comprises a single piece of sheet material cut to form a rectangular central portion having integral arms extending from the ends and sides, these arms being bent at right angles to the central portion. One pair of arms have pointed ends which are embedded in a pencil interposed between the arms, the pencil being thus attached to the holder. The other pair of arms overlie the pencil and are slightly spaced therefrom, these arms forming clips adapted to clasp the plies of a folded article with the pencil interposed between the plies.

This holder is particularly adapted for use in connection with pencils for keeping golf or other scores. The clip arms serve to hold the score card in tightly folded condition, and the pencil is always readily available merely by withdrawing the holder from the score card. The pencil point is protected as it is arranged between the plies of the score card.

Furthermore, the holder fits the score card snugly and offers no projections to interfere with slipping the score card into and out of a pocket. Mutilation or soiling of the score card is prevented as the holder serves to keep the score card tightly folded.

Other objects, novel features and advantages of the invention will be apparent from the following specification and accompanying drawing, wherein:

Fig. 1 is a perspective view of a pencil holder embodying the invention;

Fig. 2 is a perspective view of a folded score card with the pencil holder associated therewith;

Fig. 3 is a plan view;

Fig. 4 is a section on the line 4—4 of Fig.

50 2;

Fig. 5 is a section on the line 5—5 of Fig. 3, and

Fig. 6 is a plan view of the blank from which the holder is formed.

The pencil holder is formed from a single piece of sheet material such as shown in Fig. 6 which may be metal or composition of sufficient tensile strength and resiliency for the purpose. The blank is provided with a pair of pointed arms 10 which are folded into parallel relation to each other and receive the end of a flat pencil 11 into which the pointed ends are projected in order to hold the pencil firmly. The blank is also provided with arms 12 which are folded into parallel relation to overlie the wide sides of the pencil and are curved to conform generally to the contour of the pencil. These arms are slightly spaced from the sides of the pencil so that the holder may be associated with a folded score card or the like 13 as shown in Fig. 2, with the pencil inserted between the two plies of the score card and the arms 12 clasping the plies to hold the score card in folded position. The free ends of the arms 12 are curved outwardly slightly to facilitate placing the pencil holder in assembled relation with a score card. When in position on the score card, the holder keeps the score card tightly folded while the score card protects the pencil and as the holder fits tight to the edge of the score card there are no projecting portions to interfere with slipping the score card into or out of pocket.

It is of course understood that various modifications may be made in the structure of the device above described, without in any way departing from the spirit of the invention as defined in the appended claims.

I claim:

1. A pencil holder comprising a single piece of sheet material formed with a rectangular base, a pair of arms at opposite ends of the base integral therewith and perpendicular thereto, and a pencil interposed between and held by said arms, a second pair of arms at opposite sides of said base and integral therewith, said last named arms overlying said pencil and being adapted to clasp the plies of

a folded article with the pencil interposed between said plies.

2. A pencil holder comprising a single piece of sheet material formed with a rectangular base, a pair of arms at opposite ends of the base integral therewith and perpendicular thereto, and a pencil interposed between and held by said arms, said arms having pointed ends embedded in said pen-

10 cil to hold the same, a second pair of arms at opposite sides of said base and integral therewith, said last named arms overlying said pencil and being adapted to clasp the plies of a folded article with the pencil interposed between said plies.

15 3. A pencil holder composed of a rectangular sheet material central portion having integral arms bent up at the sides and ends perpendicular thereto, a pencil interposed between and held by one pair of arms and the second pair of arms overlying the pencil and being adapted to clasp the plies of a folded article with the pencil interposed between said plies.

20 4. A pencil holder composed of a rectangular sheet material central portion having integral arms bent up at the sides and ends perpendicular thereto, a pencil interposed between one pair of arms, said arms having pointed ends embedded in the pencil to hold the same, a second pair of arms overlying said pencil and being adapted to clasp the plies of a folded article with the pencil interposed between said plies.

25 5. A pencil holder composed of a single piece of sheet material comprising a base having two pairs of parallel arms integral therewith and perpendicular thereto and a pencil interposed between and held by one pair of arms, said second pair of arms overlying said pencil and being adapted to clasp the plies of a folded article with the pencil interposed between said plies.

30 In testimony whereof I have signed my name to this specification.

JOSEPH P. McENERY.
